DESIGN FOR A CHAIR.

SPECIFICATION forming part of Design No. 15,671, dated December 30, 1884.

Application filed October 13, 1884. Term of patent 3½ years.

UNITED STATES PATENT OFFICE.

FRANK F. PARKER, OF GARDNER, MASSACHUSETTS.

DESIGN FOR A CHAIR.

SPECIFICATION forming part of Design No. 15,671, dated December 30, 1884.

Application filed October 13, 1884. Term of patent 3½ years.

To all whom it may concern:

Be it known that I, FRANK F. PARKER, a citizen of the United States, residing at Gardner, county of Worcester, and State of Massachusetts, have invented and produced a new and original Design for a Chair, of which the following is a specification, reference being had to the accompanying photographic print, forming a part thereof.

10 My design relates particularly to the backs of chairs, and has for its object to attain new and beautiful effects therein.

The figure shows in perspective a chair the back of which embodies my design.

15 My design for a chair consists in a top panel for the back, the said top panel having a notched or corrugated top edge, a straight bottom edge, and an intermediate strip or band of fret-work.

20 The top piece, *a*, having the straight but notched or corrugated edge *b*, the bottom

piece, *c*, having the straight bottom edge, and the middle or intermediate fret-work strip or band, *d*, having openings, constitute the back panel and represent my design.

25

I claim—

The herein-described design for a chair, consisting in the back containing a top panel the upper edge of which, extended across the back of the chair from side to side in a straight line, is notched or corrugated, the lower edge of the panel being straight across, the central portion of the panel containing openings, as shown.

30 In testimony whereof I have signed my name 35 to this specification in the presence of two subscribing witnesses.

FRANK F. PARKER.

Witnesses:

HARLIN P. UPHAM,
JAMES A. STILES.
